UNITED STATES PATENT OFFICE.

DAVID WALKER, OF NEWARK, NEW JERSEY.

DESIGN FOR A STAIR-CARPET FASTENER.

SPECIFICATION forming part of Design No. 20,500, dated February 3, 1891.

Application filed November 6, 1890. Serial No. 370,548. Term of patent 14 years.

To all whom it may concern:

Be it known that I, DAVID WALKER, a citizen of the United States, residing at Newark, in the county of Essex and State of New Jersey, have invented and produced a new and original Design for Stair-Carpet Fastenings or Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 is a front elevation of the newly-designed stair-carpet button; and Fig. 2 is a section of the same, taken on line *x*.

The leading feature of the design consists in a stair-carpet button having the diamond shape when viewed in front elevation, the front face of which is beveled or backwardly inclined from the central perforation, substantially as shown.

A indicates the said diamond-shaped button. *b b* are the upper and lower obtuse angles thereof, and *c c* are the acute angles at the ends. At the center the button may present a perforated plane surface, as at *d*, and the edges may be oppositely beveled or inclined backward from the center toward the edges, as at *e*, and radially corrugated or otherwise ornamented, as at *f*.

What I claim as new is—

The design for a stair-button, which consists of a stair-button having the diamond shape, the front face of which is backwardly inclined from the perforated center, substantially as set forth.

In testimony that I claim the foregoing I have hereunto set my hand this 3d day of November, 1890.

DAVID WALKER.
